APPARATUS FOR STRETCHING
ELASTIC COVERS

Victor H. Hasselquist, Akron, Ohio, assignor to
The B. F. Goodrich Company, New York, N. Y.,
a corporation of New York

Application January 24, 1944, Serial No. 519,446

14 Claims. (Cl. 254—52)

1

This invention relates to apparatus for stretching elastic covers about surfaces of aircraft and is especially useful for applying ice-removing covers to the surface of airfoils.

Elastic ice-removing covers have been secured about the leading edges of wings and other airfoils by rows of hollow tubular rivets secured to the skin of the airfoil and having threaded bores for receiving screws. The covers have been provided with rows of apertures along their margins for passage of the screws, and fairing strips of metal, also having apertures for receiving the retaining screws sometimes have been applied over the margins of the covers.

Stretching of the covers to secure them in place under tension has been difficult to accomplish by hand, especially where the covers are of large size. Efforts to stretch the covers by pulling their margins from positions at the rear of the line of attaching rivets have involved difficulties because of the presence of the airfoil surface, and these difficulties have been aggravated with wings of large size.

The principal objects of the present invention are to provide tensioning of the elastic cover by pushing movement, which makes possible operation in the free space in front of the leading edge of the airfoil, to provide for pushing one of the margins to position by a leverage system secured to the attaching screws of the opposite margin and fulcrumed thereabout, to provide for simultaneously stretching a broad span of the cover, and to provide for convenience and for economy of effort and simplicity of handling.

These and other objects will appear from the following description and the accompanying drawings.

Of the drawings,

Fig. 1 is a plan view of apparatus constructed in accordance with and embodying the invention, showing the apparatus in use in association with an airfoil and elastic cover, parts being broken away.

Fig. 2 is a sectional elevation thereof, taken on line 2—2 of Fig. 1, the position of the cover before stretching being indicated in dot and dash lines.

Fig. 3 is a detail view in perspective of an anchoring hook.

Fig. 4 is a detail sectional view taken on line 4—4 of Fig. 2, parts being broken away.

Fig. 5 is a side elevation of a modification of the invention, the airfoil being shown in section, the initial position of the apparatus being shown in dot and dash lines.

2

Figs. 6, 7 and 8 are side elevations showing further modifications of the invention, the airfoil being shown in section.

Fig. 9 is a detail sectional view thereof taken on line 9—9 of Fig. 8.

Fig. 10 is a side elevation of another modification of the invention, the airfoil being shown in section.

Fig. 11 is a detail perspective view of the clamp thereof.

Fig. 12 is a side elevation of another modification of the invention, the airfoil being shown in section.

Referring to the drawings, and first to Figs. 1 to 4 thereof, the numeral 10 designates an elastic ice-removing covering in the process of being applied chordwise about the nose of an airfoil 11 in a condition of chordwise tension. The covering is at least partially of rubber or other rubber-like material and may have inflatable pockets 12 formed therein for distorting the covering to remove ice formed thereon. For securing the covering to the airfoil, the latter is provided with hollow internally threaded rivets 14 arranged in a row along its upper surface for receiving retaining screws 15, and similar rivets 16 are arranged in a row along its lower surface for receiving similar retaining screws, to engage apertures in the margins of the covering. The covering may be reinforced at its margin by stiffening beads 17, 18 of metal to distribute the load between the screws. For providing a smooth contour at the margins of the covering, metal fairing strips 20, 21 are provided, and these have countersunk openings to receive the screw heads. One margin of each fairing strip rests upon a margin of the covering when in place, and the other margin thereof rests upon the surface of the airfoil.

In attaching the covering, assuming that the airfoil is in a horizontal position and that the rivets 14 and 16 are in place, the covering is preferably first secured to the rivets 14 at the upper surface of the airfoil, and then stretched about the nose of the airfoil until its lower margin can be secured to the rivets 16. This requires considerable force, especially where the coverings are of great horizontal extent, whether the whole margin be stretched at once or the stretching be accomplished by stretching and applying the lower margin progressively.

For stretching the covering in place, a flexible tension member 25, such as a chain, is attached at one end thereof to one or more of the screws 15 which are left partially protruding for this purpose. The other end of the tension member

is secured to one end of a strut member 26. The opposite end of the strut member is adapted to engage a bifurcated hook 27 attached to the lower margin of the covering 10 with its hooked limbs engaging the upper and lower ends of a screw passed through an aperture of the covering. By exerting pressure downwardly against the strut member where it engages the tension member, a pushing force is exerted against the lower margin of the covering effecting a stretching of the covering about the nose of the airfoil.

In practicing the invention a plurality of strut members 26 and tension members 25 may be employed in unison to simultaneously stretch a wide reach of the covering or an entire covering in a single operation. For this purpose a series of hooks 27 may loosely support a bar 28, as shown in Fig. 4. Each hook is engaged about a screw 29 inserted through an aperture in the lower margin of the covering. Each strut 26 has a hook 30 on one end which engages over the bar 28. For anchoring the tension members 25 to the screws 15, hooks 31 (see Fig. 3) are provided, each having thin hooked ends 32, 33 for engaging about a pair of screws 15 above the covering. A plurality of hooks 31 may be engaged by an equalizer 34 which in turn is secured to a tension member 25. Any number of strut members 26 may be hooked over the bar 28 to push the lower margin of the covering into place.

For adjusting the relative disposition of the tension members and strut members, the struts, which are preferably of tubular form, may have longitudinal slots 35 at their outer ends, and of such width that they engage snugly between links of chains employed as the tension members but prevent the chain sliding therethrough. In starting the stretching operation, the hooks 27 are attached to the lower margin of the covering, which hangs free as shown in dot and dash lines in Fig. 2, the strut members 26 are hooked over the bar 28 engaged by the hooks 27, and the tension members 25 are attached to the strut members at the desired position. The strut members may then be forced downwardly by pressure applied at the portion thereof where they engage the chain tension members to stretch the covering.

For applying a constant pressure, an eyebolt 36 may be provided at the outer end of a strut member, and weights 37 may be secured to the eyebolt. With this arrangement, weights may be applied until the covering is stretched to a position where the screws in its lower margin are in alignment with rivets 16. The stretching apparatus is then kept in place while an operator enters the screws in the rivets and turns them partly into place. It is found that in the stretched position the apparatus is nicely balanced and may be shifted easily by hand to bring the screws into exact alignment with the rivets.

After the screws are started, the stretching apparatus is removed and the screws driven in place.

Where the airfoil is in horizontal position and it is desired to apply the lower margin of the covering first, the stretching apparatus of Fig. 5 is desirable. Referring to this figure of the drawing, the strut member 40 has a hooked end 41 for engaging over a bar 42 which engages hooks 43 similar in construction to the hooks 27 of Fig. 4. At the opposite end of the strut, the strut is formed with a yoke 44. A shackle 45 is pivotally mounted on the yoke and a tension member 46 has one end secured to the shackle and the other end to an anchoring hook 47, similar to the hook shown in Fig. 3.

With the hook 47 anchored to screws 48 by which the lower margin of the covering 49 is secured to the airfoil, and the strut 40 engaging the bar 42, a force exerted upwardly against the strut 5 at the yoke end thereof stretches the covering 49 by pushing its upper margin about the upper surface of the airfoil while the tension member 46 fulcrums about the hook 47 providing the reaction force.

10 For holding the apparatus at its position of final adjustment to permit the operator to secure the screws 50 in place, a standard 51 is provided having a base 52 resting on the floor. A clamp collar 53 is slideably mounted on the standard but may be locked thereto at any desired position by a clamp screw 54. The collar 53 extends through the yoke 44 which bears thereon, a shoulder being provided thereon for supporting it. The arrangement is such that with the screw 54 loosened the collar 53 with the strut member may be lifted with respect to the standard to push the upper margin of the covering into its position of attachment and the collar may then be secured to the standard to free the workman for securing screws 50 in place.

In the form of the invention of Fig. 6, the strut member 60 has a hooked end 61 for engaging over a bar 62 which in turn engages the hooks 63 which engage the screws 64 passed through the lower unsecured margin of the covering 65. The upper margin of the covering is secured to the airfoil 66 by screws 67. Hooks 68, similar to the hooks of Fig. 3, are secured about the screws 67. The strut member 60 has a vertical arm 68 integral therewith. A tension member 68a has one end secured to the hooks 68 and the other end secured to the arm 68. Pressure applied downwardly on the outer end of the strut member 60 causes the apparatus to fulcrum about the hooks 63 and the lower margin of the covering is pushed into final position by stretching of the covering. The retaining screws 64 are then entered in the rivets 69 and the stretching apparatus is removed. Whereupon the screws 67 and 64 are driven home.

45 In the form of the invention shown in Fig. 7, the covering 70 is shown as attached along its lower margin to an airfoil 71 by screws 72 engaging hollow rivets 73. The upper margin of the covering is to be secured to hollow rivets 74 by 50 similar screws engaging apertures 75 in the margin. For stretching the covering a stiff tension member 76 has a claw 77 fixed to one end thereof for engaging under the head of one of the screws 72. It has a clamp collar 78 at its opposite end adapted to engage over a bar 79 and to be clamped thereto at any position therealong by a hand screw 80. Mounted on the bar is a second clamp collar 81 adapted to be clamped thereto by a hand screw 82. The collar 81 is also provided with a radially-extending arm 85 and an ear 86 adjacent thereto. A strut member 87 is hinged to the ear 86. A tension screw 88 is hinged to the arm 85 and has a wing nut 89 threaded thereon. A compression coil spring 90 surrounds the tension screw between the wing nut and the strut 87.

Hingedly mounted on the end of the strut 87, as at 94 is a shoe 91 adapted to frictionally engage the outer surface of the covering 70. The 70 shoe has a pad 92 of friction material, such as rubber on its face. A lever 93 is fixed to the strut 87 near the friction shoe. The arrangement is such that the collar 81 and the wing nut 89 may be adjusted to engage the surface of the covering near its upper margin with some

pressure and the lever 93 may then be forced to the left in Fig. 7 to cause the apparatus to rotate about the claw 72 as a center in a counter-clockwise direction with the pad 92 engaging the covering and pushing it about the airfoil 71 in the direction of the rivets 74, thereby stretching the covering to a position where the screws may be entered in the hollow rivets 74 through the apertures 75.

The apparatus shown in Fig. 8 is adapted to push both margins of the covering 140 into place about the nose of the airfoil 141 simultaneously to align its screw apertures with the threaded hollow rivets 142, 143 secured to the skin of the airfoil. For this purpose, a pair of parallel tubular tension members 144, 145 have claw hooks 146, 147 secured to ends thereof adapted to engage screws inserted in the rivets 142, 143. Within the tension members are strut members 148, 149. The strut members each has a laterally projecting finger 150 which extends through a longitudinal slot 151 formed in the wall of the tubular tension member and is adapted to engage in an aperture in the margin of the covering. Each strut member is also formed with a rack 152 for propelling it along the tension member in which it is adapted to slide.

At a position along each tension member, a housing 155 is fixed to the member and has bearings 156 for rotatably supporting a shaft 157 which extends through both housings. A gear 158 is slideably mounted on the shaft 157 which has a keyway 159 for engaging a feather key fixed to the gear. The gear extends through a slot in the tension member and meshes with the rack of the strut member. A crank 160 is fixed to the shaft 157 for rotating it. The arrangement is such that by rotating the shaft 157 the strut members may be advanced along the tension members to push the margins of the covering toward the hooks 146, 147 and thereby stretch the covering into place. For holding the tension members in properly spaced apart relation, collars 165, 166 are provided at each side of each housing and have set screws for securing them to the shaft in any position of adjustment. For locking the racks in any position of adjustment, a pawl 161 is pivoted on the housing 155.

In the use of this form of the invention, the apparatus is adjusted so that the claws 146, 147 engage screws inserted in the rivets 142, 143. The fingers 150 are inserted in screw holes in the opposite margins of the covering. The crank 160 is then operated to advance the strut members and the margins of the covering to a position where the screw holes align with the screws. Screws may then be inserted in adjacent screw holes to those engaged by the fingers 150 to hold the covering in place.

Referring to Figs. 10 and 11, the covering 110 is shown as secured at its upper margin to the airfoil 111 by screws engaging in the hollow rivets 112. A hook member 113, similar to that shown in Fig. 3 is hooked under the fairing strip 114 about screws entered in the hollow rivets 112. The lower margin of the covering is gripped by a clamp member 117 (see Fig. 11) having a hook 118. For pushing the lower margin of the covering into place a tension member 115 is provided with a claw 115a for engaging a screw entered in a hollow rivet 117. The tension member 115 has a pair of threaded ears 118, 119 through which a threaded thrust member 120 extends. A crank 121 is fixed to the thrust member. A swivel pressure plate 122 is mounted on

the end of the thrust member and is formed with a hook for engaging over a bar 123. The bar 123 is adapted to engage simultaneously a plurality of the clamping members by their hook portions 118. Each clamp member has a stationary jaw 124 and a movable spring jaw 125 adapted to be pressed toward the stationary jaw by a cam 126 actuated by a lever 127.

For supporting the apparatus, a flexible tension member 128 is attached to the hook member 113 and has its lower end secured to the ear 119. The arrangement is such that when the crank 121 is rotated in one direction, the bar 123 is forced to the left in Fig. 10 against the hooks 118 forcing the lower margin of the covering into place where the screws may be entered in the tubular rivets 117.

In the form of the invention shown in Fig. 12, one margin of the covering 170 has been secured by screws entering hollow rivets 171 secured to an airfoil 172 which is located in a position with its nose downwardly. For pushing the other margin into a position where perforations for screws in the margin are over hollow rivets 173, a bar 174 having a series of hooks 175, similar to the hooks 27 shown in Fig. 4, is secured by means of the hooks engaging screws inserted in the perforations of the margin of the covering.

A jack 176, preferably of the type in which a moveable step 177 is adapted to be adjusted along a strut member 178 by operation of a handle 179, has a ball-joint 180 connecting it to a non-slipping floor plate 181. The floor plate has a suction rubber shoe 182 for engaging the floor 183 at any position. The arrangement is such that the moveable step 177 may be engaged under the bar 174 and adjusted up the strut member 178 to push the margin into place so that the screws can be entered in the hollow rivets 173.

Due to the moveable floor plate and the ball connection, the strut 178 may be adjusted to any desired angular relation to the floor. This has the advantage of providing for lateral adjustment as well as vertical adjustment of the margin of the cover to align the screw holes accurately with the hollow rivets.

Variations may be made without departing from the scope of the invention as it is defined by the following claims.

I claim:

1. Apparatus for stretching an elastic covering about a curved surface while a margin of the covering is restrained against yielding by securing means engaging said surface, said apparatus comprising means for holding the opposite margin of the covering, and means including a tension element having attachment to said securing means for pushing said holding means in a direction to stretch the covering, said pushing means including said tension element being fulcrumed at said securing means for movement as a unit about said securing means.

2. Apparatus for stretching an elastic covering to a curved surface while a margin of the covering is restrained against yielding by securing means engaging said surface, said apparatus comprising means for holding the opposite margin of the covering, means including a tension element having attachment to said securing means for pushing said holding means in a direction to stretch the covering, and means for supporting the pushing means including said tension means for movement as a unit about said securing means.

3. Apparatus for stretching an elastic covering

about a curved surface while a margin of the covering is restrained against yielding, said apparatus comprising means for holding the opposite margin of the covering, and means for positioning said opposite margin in place, said last-named means comprising a strut member engaging said opposite margin, a tension member connecting said strut member to an element on the surface, and means for shifting the positions of said strut and tension means to stretch the covering.

4. Apparatus for applying an elastic covering to a curved surface, said apparatus comprising tension means including means for engaging a projection on the surface and a flexible member extending therefrom, and strut means for engaging at one end thereof a margin of the covering and at the opposite end a free portion of said flexible member.

5. Apparatus for applying an elastic covering to a curved surface, said apparatus comprising tension means including means for engaging a projection on the surface and a flexible member extending therefrom, strut means associated with said tension means, and means for moving said tension and strut means in a direction to stretch the covering.

6. Apparatus for applying an elastic covering to a curved surface, said apparatus comprising tension means including means for engaging a projection on the surface and a flexible member extending therefrom, strut means associated with said tension means, means for adjusting said strut and tension means as a unit in a direction to stretch the covering, and means in addition to said tension means for holding said strut and tension means in a position of adjustment.

7. Apparatus for stretching an elastic covering about the leading edge of an airfoil while a margin of said covering is retained by elements in the surface of the airfoil, said apparatus comprising means for engaging said covering at a position spaced from said elements chordwise, and means for pushing the engaging means to stretch the covering.

8. Apparatus as defined in claim 7 in which the covering-engaging means comprises a friction pad.

9. Apparatus as defined in claim 7 in which the covering-engaging means comprises hooks for engaging projecting elements in the margin of said covering.

10. Apparatus for stretching an elastic covering about the leading edge of an airfoil while a margin of said covering is retained by elements in the surface of the airfoil, said apparatus comprising means for engaging said covering at a position spaced from said elements chordwise, and means for pushing the engaging means to stretch the covering, the last said means including reaction means for engaging said elements.

11. Apparatus for stretching an elastic covering about the leading edge of a curved surface such as an airfoil while a margin of the covering is restrained at one side of said leading edge against yielding, said apparatus comprising means for holding the opposite margin of the covering, and strut means connected to said holding means including means engageable with a projection on said surface at the other side of the leading edge and operable from in front of said projection to direct said opposite margin of the covering to said projection.

12. Apparatus for stretching an elastic covering about the leading edge of a curved surface such as an airfoil while a margin of the covering is restrained at one side of said leading edge against yielding, said apparatus comprising means for holding the opposite margin of the covering, a member engageable with a projection on said surface at the other side of the leading edge, and strut means connected to said holding means and having a pivotal mounting with said member for swinging movement from in front of said projection to direct said opposite margin of the covering to said projection.

13. Apparatus for stretching an elastic covering about a curved surface while a margin of the covering is restrained against yielding by securing means at said margin engaging said surface, said apparatus comprising means for engaging the opposite margin of the covering, and swinging means including a tension element having at one end thereof attachment to said surface at said securing means, and strut means having one end engaging said tension element at a position remote from said securing means and the opposite end engaging the free margin of the covering, said swinging means being fulcrumed at said securing means for movement as a unit thereabout.

14. Apparatus for stretching an elastic covering about the leading edge of an airfoil, said apparatus comprising elements connected to each other for engaging said covering at positions spaced-apart chordwise, and means for moving an element with respect to the other for stretching said covering upon said surface, said means comprising a strut element extending forwardly of the airfoil for manipulation in advance of said leading edge.
